PAPER AND THE LIKE WEB SEVERING
MECHANISMS

Roy Dennis Davies, Hillborough, Herne Bay, Kent, England, assignor to Moore Business Forms, Inc., Niagara Falls, N.Y., a corporation of Delaware

Filed Mar. 12, 1964, Ser. No. 351,315

1 Claim. (Cl. 225—100)

This invention has reference to paper and the like web severing mechanisms of the kind, sometimes referred to as Bursters, in which a continuous web of paper with cross perforations is fed between two pairs of rollers of which the outfeed pair of rollers have a larger feeding speed than that of the infeed pair of rollers. The rollers are so disposed that the paper web is severed across the lines of cross perforations with a bursting action.

It is an object of the present invention to provide an improved form of paper severing mechanism.

It is another object of the present invention to provide an improved form of paper severing mechanism which may be easily adjusted to enable continuous webs to be severed into different form lengths.

According to the present invention a paper or like web severing mechanism comprises a pair of infeed rollers and a pair of outfeed rollers, drive means for driving the outfeed rollers at a higher speed than the infeed rollers and a pair of spaced arcuate guides between which the paper is fed between the rollers.

One of the features of novelty of the invention is the provision in a vertical arcuate burster as described, of receiving and delivering means both disposed upon the same side of the machine and the sheet delivery receptacle positioned above the support for the web to be fed through the machine. This provision has at least two advantages, one in permitting the machine to be attended by a single operator, and another the ability to position the machines in back-to-back relationship or to locate a machine with its back toward the wall of the room, all effecting economies in space and labor.

A paper web severing mechanism in accordance with the invention will now be described by way of example with reference to the accompanying drawings wherein:

FIG. 1 is a sectional side view of the mechanism, and

FIG. 2 is a plan view with the cover removed.

The paper severing mechanism comprises an infeed tray 1 on which for example, a pack of a continuous paper stationary web 2 to be severed is stacked. A pair of parallel spaced infeed guides 3 are located above the stacking tray. A guide roller 4 is mounted on the infeed end of these guides 3 and a curved bracket 5 is located around the centre part of the roller 4 to divert the web into the guides 3. Sleeves 6 are secured on the roller 4 and are adjusted so as to be spaced apart a distance slightly greater than the width of the stationary web to be severed. The parallel guides consist of a lower flat plate and a flat plate resting on the lower flat plate. The upper flat plate has flanges at its sides deeper than the thickness of the stationary web being severed so that the plates are spaced apart a distance slightly greater than the thickness of the web. These guides 3 are mounted to guide the web in a horizontal plane and in a straight line path into a plurality of pairs of infeed guides 7 which direct the web into a pair of spaced guides 8 arranged in an arc of a circle. This arc extends for approximately 90° and the guides 8 are so arranged that the web is fed into the guides in a vertical direction and out of the guides in a horizontal direction. The arc has a radius of about eight inches. As shown, nine pairs of guides are spaced across the paper severing mechanism,

2

and each guide has a width of about three quarters of an inch and each pair of guides are disposed apart by a distance of about one eighth of an inch throughout their arcuate lengths.

5 A pair of outfeed rollers 9 and 9' are mounted in a fixed support at the outfeed end of the arcuate guides 8 one vertically above the other. These rollers 9 and 9' are each castellated, that is to say they have cylindrical parts of a large diameter separated by cylindrical parts of a smaller diameter. The large diameter parts of one roller are opposite the large diameter parts of the other roller. The large and small diameter parts each have a length of about one inch. The upper roller 9 is of steel and the lower roller 9' is of rubber. The upper roller 9 is mounted in a bearing with a cooperating screw indicated diagrammatically at 9a so arranged that the upper roller can be adjusted to be in frictional driving engagement with the lower roller.

A stripper guide 10 is located adjacent the outfeed 20 side of the lower outfeed roller 9'.

The outfeed rollers 9 and 9' and guides 8 are supported between side plates 11. A pair of infeed rollers 12 and 12' are mounted between a pair of pivoted supporting plates 13 each of which is pivoted to a cross 25 shaft 14 mounted at the centre of the circle whose periphery is constituted by the arcuate guides 8. The outer roller 12 is in frictional driving engagement with the inner roller 12'. These pivoted plates 13 carry the infeed rollers 12 and 12' which are also of castellated 30 form. A cross bar 15 is mounted between the two pivoted plates and two catch bars 16 are mounted on this cross bar. Each catch bar 16 is urged by a spring 17 outwardly and is arranged to be located in one of a plurality of holes 18 in the side plates 11 to locate the infeed rollers 12 and 12' circumferentially around the 35 pairs of parallel arcuate guides 8. A handle 19 on the cross bar 15 facilitates adjustment of the rollers. By this means the relative arcuate distance apart of the infeed and outfeed rollers can be adjusted to accommodate for 40 severing of different form lengths of continuous webs.

The infeed roller 12' and outfeed roller 9' are driven by an electric drive motor 20 with a connecting drive 21 to a drive sprocket 22 on the shaft 14 at the centre of the circle on which the arcuate guides lie. An endless belt connection 23 is made to the inner feed roller 12' of the infeed guides and this inner feed roller 12' drives the outer feed roller 12 by friction. A drive belt connection 24 is also made from the drive sprocket 22 to the inner roller 9' of the outfeed roller. The outer roller is likewise driven by friction with the inner roller. The drive is connected so that the outfeed rollers are driven faster than the infeed rollers. The drive shaft 24a to the drive motor 20 is extended outside the side plates 11 and a feed wheel 25 is affixed to the end of this shaft 55 so that the rollers can be driven manually.

A feed tray 26 is located at the outfeed side of the outfeed so that form lengths detached from the web 2 fall on to the tray in stacks. A guide 27 is adjustably mounted on the tray 26 so that the tray can accommodate different 60 sizes of form lengths. Three stacking rods 28 are located on shaft 29 to assist in stacking the form lengths.

A pivoted cover 30 is arranged over the guides to prevent the mechanism operator from becoming entangled with the rollers and other moving parts.

65 When a continuous stationary web is to be severed by bursting action, the continuous web in pack form is loaded onto the infeed tray 1 and threaded between the guides 3 and the guides 7 to the arcuate guides 8 and the infeed rollers 12. The leading edge of the web is then fed between the infeed rollers and arcuate guides 8 toward the outfeed rollers by rotation of the feed wheel 25. The motor is then started and the web is fed by the infeed

roller until the leading edge of the web reaches the outfeed rollers. The outfeed rollers then grip the leading edge. Because the outfeed rollers are feeding at a rate faster than the infeed rollers a snatch action is given to the web which causes the leading form length to be detached from the remainder of the web across the tear off perforation. Because the webs are being fed in an arcuate path the positioning of the arcuate guides facilitate the initiating of the bursting action which is continued across the cross perforation. It is required that the position of the infeed rollers shall be so arranged that a tear off perforation shall be located between the two rollers when the leading edge of the leading form length engages between the outfeed rollers. It is of course, also required that a single tear off perforation shall be located between these two rollers at this time.

When it is required to burst a different form length the position of the cross bar 15 is adjusted by moving the two catch bars together to move the outer ends of these catch bars 16 from the appropriate pair of holes 18 in the side plates 1. The cross bar 15 is then moved to the position required by the length of the form to be severed, that is that the distance part of the two rollers shall be slightly in excess (measured around the arcuate path of the guides) of the length of the form length to be severed and the catch bars 16 are located in another pair of holes 18. The stationary web of the different form length can then be loaded into the severing mechanism as hereinbefore described.

It has been found that it is desirable that the outfeed rollers shall not be loaded at an arcuate distance of more than approximately 90° around the arcuate guides from the outfeed rollers as bursting then tends to occur on the leading side of the perforation. Also, as already mentioned, advantages accrue in locating the web supply support at the lower portion of one side of the machine and the sheet pile receiving support upon the same side of the machine but above the web feed position.

It has also been found desirable to include a counterbalancing means, indicated diagrammatically at 32 which acts to counterbalance the infeed rollers 12 to permit them to be easily adjusted. Thus by altering the position of these rollers different form lengths of the stationary web being bursted can be easily accommodated. This counterbalancing means 32 may comprise a torsion spring.

What I claim is:

A paper or like web-severing machine comprising a supporting frame; means on said frame for feeding, guiding, and severing a web and for delivering sheets severed from said web, said means adapted to receive a web moving in one direction, operate thereon, and deliver the severed sheets in the opposite direction; the points of reception of said web and delivery of said sheets by said means being vertically spaced from each other and upon the same side of said machine, the delivery point being above said receiving point; said means including a web and sheet guide of generally vertically arcuate configuration joining said points of reception and delivery, a pair of outfeed rollers and a pair of infeed rollers, means for supporting said pairs of rollers at spaced points along said guide, means for adjusting the position of at least one of said pairs of rollers along said arcuate guide to space the infeed and outfeed rollers at appropriate distances apart for the selected sheet length; means for driving said outfeed rollers at a greater speed than said infeed rollers, a sheet web support adjacent the receiving point and a sheet pile support adjacent the delivery point and above the web support on the same side of the machine.
